[57] CLAIM

The ornamental design for a portable mirror with rear suction support, as shown.

DESCRIPTION

FIG. 1 is a front elevational view of a portable mirror with rear suction support showing my new design;

FIG. 2 is a side elevational view thereof;

FIG. 3 is a rear elevational view thereof;

FIG. 4 is a top plan view thereof;

FIG. 5 is a front elevational view of the modified embodiment of the mirror disclosed in FIG. 1;

FIG. 6 is a side elevational view thereof;

FIG. 7 is a rear elevational view thereof; and,

FIG. 8 is a top plan view thereof.

FIG. 1**FIG. 2****FIG. 3****FIG. 4**

FIG. 5**FIG. 6****FIG. 7****FIG. 8**
